UNITED STATES PATENT OFFICE.

EDWARD PETER JONES, OF ELLESMORE PORT, AND ARTHUR HENRY JACKSON, OF MANCHESTER, ENGLAND.

MACHINE FOR SHEARING METAL BARS.

Application filed June 26, 1925, Serial No. 39,826, and in Great Britain September 3, 1924.

This invention relates to multiple-head shearing machines such as used in sheet and tinplate works for dividing a plate transversely into several sheets having a series 5 of blades fixed to a bed and a corresponding number of blades carried by a reciprocating slide.

In such machines as hitherto constructed the several cuts of the plate or bar were 10 made simultaneously at each stroke of the machine.

According to this invention a multiple shearing machine is provided into which a long bar may be fed sideways with the cutting blades so set in stepped relation to one another as to act in succession and cut the bar into a number of short lengths in succession at a single stroke of the machine.

The machine comprises a plurality of cutting or shearing heads with upper and lower blades disposed transversely to its longitudinal axis and with the upper blades set at different levels or in stepped relation to one another to cut a long bar into a number 25 of short lengths one at a time, one set of cutting blades being carried on a reciprocating cross-head the shearing heads being either permanently set to cut all bars to one length or mounted on slides so that they can 30 be adjusted as required to cut bars to any desired length a rack or screw and differential gearing being provided to move and adjust the shearing heads to the desired position.

The invention will be fully described with reference to the accompanying drawings.

Fig. 1 is a front elevation of multiple-bar shearing machine (with front plate removed) of the form in which the shearing heads are permanently set to cut one length 40 of bar.

Fig. 2 is a plan of cross head for carrying top shear blocks.

Fig. 3 is a transverse sectional elevation 45 of same.

Fig. 4 is a front elevation of multiple bar shearing machine with adjustable shearing heads adapted to cut various lengths of bar.

Fig. 5 is an end elevation of same viewed 50 from left end of machine.

Fig. 6 is a transverse sectional elevation of same viewed from left end of machine.

Fig. 7 is an end elevation partly in section, viewed from right end of machine.

Fig. 8 is a plan of bracket carrying the 55 bottom shearing block.

Fig. 9 is a front elevation of one of the cutting heads A.

Fig. 10 is a front elevation of the balanced movable part of the cross-head extension.

Fig. 11 is a plan of same.

Fig. 12 is a transverse section through the delivery end of the machine.

Fig. 13 is a section of skip U.

In the form shown in Figs. 1 to 3 the machine is designed to cut one length of bar only, the cutting heads A being permanently set or fixed at a given distance apart and is constructed with two main end frames B, B¹ 70 connected by cross-bed D at the bottom and a cross-bar C at the top both securely bolted to the end frames B, B¹. The end frames are formed with slides b, b¹ in which a reciprocating cross-head or sliding member E is mounted and adapted to slide up and down. To the cross bed D a number of shear blades d are affixed at right angles to its longitudinal axis and to the reciprocating cross head E a corresponding number of shear blades e 80 are affixed forming shear heads A with pairs of shear blades d, e at right angles to the front line of the machine. The pairs of shear blades are equal in number to the number of short lengths of bar to be cut and are 85 spaced at the proper distance apart to produce the lengths of bars required.

A driving or operating shaft F driven by spur wheel f is journaled in bearings in the end frames B, B¹ and upon it are mounted two eccentrics f¹ connected to the reciprocating cross head E by links f² and by which it is operated.

A sloping skid G is fitted in front of the machine down which the bars G¹ are fed 95 sideways into the machine between the blades d, e of the shear heads A and it is found desirable to incline the shear blades d, to the same extent in continuation of the slope of the skid (say about 30° from the horizontal line) and the reciprocating cross-head E is inclined to the same extent and in the same direction.

The bottom shear blades d are all set at

the same level to support a bar resting upon them but the top shear blades *e* are each set at a higher level than the one preceding it so that each pair of blades will come into operation in succession and although the bar may cut into say six short lengths at a single stroke of the machine only one cut takes place at a time.

At one end of the machine a stop *H* is fitted to position the bar upon the bottom blades *d* before being cut. The end stop *H* is moved to and fro by a cam *h* on the shaft *F* through the links and levers *h*¹ the lever being held in contact with the cam by a spring. As each bar is slid in between the pairs of shear blades on to the bottom blades *d* the stop is brought against it to position it, bringing the end the desired distance from the last pairs of blades. Any scrap or short length cut off at the other end falls down the chute *h*². The cut lengths fall down the chutes *h*³ where they can be collected or be carried away on a travelling conveyer such as shown in Figs. 4 and 12.

The machine is fitted with a clutch *K* operated by a treadle *k* so that it may be run continuously or intermittently and the cross-head *E* which carries the top shear blades *e* is counterbalanced by weights *W* carried on levers *w* and connected to the cross-head by links and buffer springs *w*¹.

In the form shown in Figs. 4 to 13 the machine is designed to cut any desired length of bar and the cutting heads *A* with the shear blades *d*, *e* are adjustable in position upon the cross-bed *D* and cross-head *E* respectively as required to produce different lengths of bars.

The machine is constructed with two main end frames *B*, *B*¹ connected by cross-bed *D* at the bottom and cross-bar *C* at the top both securely bolted to the end frames *B*, *B*¹. The end frames are formed with inclined slides *b*, *b*¹ in which a reciprocating cross-head *E* is mounted and adapted to move up and down and the cross-head is counterbalanced by weights *W* carried on levers *w* and connected to it by links and buffer springs *w*¹.

The cutting heads *A* each comprise a pair of brackets or saddles, a lower bracket *M* mounted upon and adapted to slide along a slide *m* on the cross-bed *D* and an upper bracket *N* mounted upon and adapted to slide along a slide *n* on the cross-head *E* so that the position of the cutting heads can be adjusted in relation to one another to alter the distance between them according to the length of bars to be cut. The lower sliding bracket *M* is made with a recess or gap *m*¹ into which a projection *n*¹ on the upper sliding bracket *N* fits which retains the shear blades *d* and *e* in shearing contact and also ensures that the upper bracket *N* will move in unison with the lower bracket

M. The shear blade *d* is affixed to and carried by the lower sliding bracket *M* and the shear blade *e* is affixed to and carried by the upper sliding bracket *N*, the blades being at right angles to the front line of the machine.

The bottom shear blades *d* are all fixed at the same level to support a bar resting flat upon them and the top shear blades *e* are each set at a higher level than the one preceding it so that each pair of blades will come into operation in succession at each stroke of the machine only one cut taking place at a time. The blades are set at an inclination of about 30° to the horizontal to receive a bar from an inclined skid (such as *G* in Fig. 3).

The cutting heads *A* are moved to and fro on the slides and spaced thereon by power. A toothed rack *O* is fitted to the cross-bed *D* and each of the lower brackets or saddles *M* carries a pinion *m*² which gears with the rack and is driven from a worm *L* on a longitudinal shaft *P* through worm wheel *p*¹ and gears *p*² and as the upper bracket or saddle *N* engages with the lower bracket *M* the two brackets and the shear blades slide together. The shaft *P* is mounted in front of the machine and may be driven by an electric motor *P*¹ or other source of power.

A stop *H* is fitted at one end of the machine operated by a cam *h* and lever *h*¹ to position each bar as it is placed on the bottom blades to be cut, the lever being held in contact with the cam by a spring.

For readjustment of the cutting heads *A* for different lengths into which a bar is to be cut it will be evident that as the bars are always brought to the same position by the stop *H* at one end, if equal spacing of the pairs of shear blades *d* and *e* is to be maintained the cutting head *A* which is furthest from the stop *H* must travel a greater distance in the same time along the bed than the cutting heads which are nearest to the stop. This necessary differential movement is obtained by the use on the lower brackets or saddles *M* of gearing of different ratios on each, to drive, each successive pinion *m*² on the rack *O* faster than the one preceding it.

The machine is fitted with a number of cutting heads *A* sufficient to cut the bars into the shortest lengths and greatest number of pieces required. When longer lengths and fewer number of pieces are required and the cutting heads are spaced at their wider distances apart some of those furthest from the stop *H* will not be required for cutting. To accommodate and support the cutting heads *A* not required for cutting the cross-bed *D* may be extended at *D*¹ and a fixed extension *E*¹ of the reciprocating cross-head *E* is provided to receive the top brackets

each bracket engaging with the rack and worm gear and pinions to rotate such wheel to traverse the bracket into desired position.

5. Apparatus for shearing metal bars into a plurality of short lengths constructed with a plurality of shearing cutting heads with upper and lower cutting blades disposed transversely to the longitudinal axis of the machine and the lower cutting blades set at an inclination to the horizontal in combination with a sloping skid from which to deliver the bars sideways to the cutting blades.

6. Apparatus for shearing metal bars into short lengths constructed with a plurality of shearing cutting heads disposed transversely to the longitudinal axis of the machine, a stationary cross bed upon which all the lower blades are set to the same level and at an inclination of about 30° to the horizontal to receive a long bar across them, a reciprocating cross head sliding in a plane at a corresponding inclination to the vertical to which the upper cutting blades are affixed each blade in succession a greater distance from the corresponding lower blade to cut a long bar into a plurality of short lengths at successive cuts on a single stroke of the machine.

7. Apparatus for shearing metal bars into short lengths constructed with a plurality of shearing cutting heads the blades of which are disposed transversely to the longitudinal axis of the machine, a stationary cross bed provided with slides, a plurality of sliding brackets mounted thereon, a cutting blade affixed to each sliding bracket, a reciprocating cross-head provided with slides, a plurality of sliding brackets mounted thereon, a cutting blade attached to each sliding bracket, the lower cutting blades set at an inclination of about 30° to the horizontal to receive the bars and the reciprocating cross head sliding in a plane at a corresponding inclination to the vertical, in combination with a sloping skid disposed at right angles to the longitudinal axis of the machine from which to deliver the bars sideways to the cutting blades.

8. Apparatus for shearing metal bars into short lengths constructed with a fixed cross-bed and a reciprocating cross-head, slides on the said cross-bed and cross-head, a number of brackets mounted upon and adapted to be moved to and fro along the slide on the cross-bed and a number of brackets mounted upon the slide on the cross-head, shear blades fitted transversely to the sliding brackets and means to traverse the brackets along the slides.

9. Apparatus for shearing metal bars into short lengths constructed with a plurality of cutting or shearing heads mounted upon a

fixed cross-bed and reciprocating cross-head and adapted to slide thereon, an extension 65 of the cross bed, and a fixed extension of the cross-head to hold the brackets of the cutting head when out of action, a connecting piece adapted to slide vertically between the reciprocating cross-head and its fixed extension and means to traverse the shearing heads as required to position them for cutting the length of bar required.

10. Apparatus for shearing metal bars into short lengths constructed with a plurality of shearing or cutting heads provided with transversely set blades and mounted upon a fixed bed and reciprocating cross-head each shearing or cutting head comprising a lower bracket or saddle fitted with a pinion to engage a rack on the cross-bed to traverse it along the cross-bed, and a worm, worm wheel and gears to rotate the pinion, and an upper bracket or saddle to traverse the cross-head engaging with the lower bracket so that the two will traverse in unison.

11. Apparatus for shearing metal bars into short lengths constructed with a plurality of shearing cutting heads the blades of 90 which are disposed transversely to the longitudinal axis of the machine, a stationary cross bed provided with slides, a plurality of sliding brackets mounted thereon, a cutting blade attached to each sliding bracket, means to connect each pair of upper and lower sliding brackets and means to 95 traverse them in unison, chutes to direct the cut bars from the shearing blades, a travelling conveyor to receive the cut bars and carry them away from the machine, and a receptacle for the cut bars into which the conveyor delivers them.

12. Apparatus for shearing metal bars into short lengths constructed with a plurality of shearing cutting heads the blades of which are disposed transversely to the longitudinal axis of the machine, a stationary cross bed provided with slides, a plurality of sliding brackets mounted thereon, a cutting blade affixed to each sliding bracket, a reciprocating cross-head provided with slides, 110 a plurality of sliding brackets mounted thereon, a cutting blade attached to each sliding bracket, eccentrics, balance weights, levers, links and buffer springs by which the reciprocating cross head is operated substantially as described.

In testimony whereof we have hereunto set our hands.

E. PETER JONES.
A. H. JACKSON.

or saddles N. The extension E¹ is at the same level and in alignment with the cross-head E when the latter is in its raised position. The rack O is extended along the extension D¹ of the cross-bed D and the pinions m² of the lower brackets M will remain in gear with the rack and the brackets will slide on to the extension.

To avoid the risk of one of the top brackets 10 or saddles N remaining partly on the moving cross-head E and partly in the fixed extension thereof E¹, a balanced intermediate sliding section piece R is fitted on to the fixed extension E¹ and between it and the 15 end of the cross head E.

The intermediate section sliding piece R is mounted on the slide r on the end of the fixed extension E¹ and has a width slightly greater than that of the top shear bracket or 20 saddle N.

Thus if the bracket or saddle N is partly upon the cross-head E and partly upon the sliding piece R the latter will move up and down with it and prevent breakage while 25 the brackets or saddles which have moved on to the extension E¹ will remain at rest. An adjustable stop r¹ is fitted to the extension piece E¹ to ensure that the piece R and cross-head E are in alignment at the top of 30 the stroke.

A chute h³ with curved or inclined face is fitted to each of the lower brackets or saddles M and travels with it. Down this chute the cut lengths of bars fall preferably 35 on to a travelling conveyor S placed below the floor level and from which the cut bars may be delivered into a skip or other receptacle.

The bearing p³ of the shaft P may be 40 drawn along the shaft by a bar T fitted with a pin t with which a bracket t¹ engages as the shearing heads are moved back towards the machine.

The operation of the machine is controlled 45 by a clutch K and pedal h so that it can either be run continuously or making one cut at a time when desired.

The cut bars are delivered endways down the inclined chutes h³ on the machine on to 50 the bend of a travelling conveyor S which in turn discharges the bars on to an inclined chute S¹ which delivers them endways into a skip U. This skip U which has no back or front plates but merely consists of two 55 sides and a bottom is suspended from an electric traverser V controlled by a man standing on the floor at one side of the inclined chute, in full view of the skip. The skip is traversed from side to side and gradually lowered as it becomes filled with the 60 cut bars which enter it endways and lie horizontally. The impact of the bars is absorbed by means of a heavy cast iron plate Y against the back wall of the trench Y¹ in 65 which the skip is suspended. After the skip

is full it is moved away by the traverser and another skip got into position. The hooks V¹ for suspension of the skip U from the traverser V are also operated by electric power controlled by the man who operates 70 the traverser.

What we claim as our invention and desire to protect by Letters Patent is:—

1. Apparatus for shearing metal bars into short lengths constructed with a plurality of shearing cutting heads the blades of which are disposed transversely to the longitudinal axis of the machine, a stationary cross bed upon which all the lower blades are set to the same level to receive a long bar, a reciprocating cross-head to which the upper cutting blades are affixed, each blade in succession a greater distance from the corresponding lower blade to cut a long bar into a plurality of short lengths by successive cuts at a single stroke of the machine. 80

2. Apparatus for shearing metal bars into short lengths constructed with a plurality of shearing cutting heads the blades of which are disposed transversely to the longitudinal axis of the machine, a stationary cross bed provided with slides, a plurality of sliding brackets mounted thereon, a cutting blade affixed to each sliding bracket, a reciprocating cross-head provided with 90 slides, a plurality of sliding brackets mounted thereon, a cutting blade attached to each sliding bracket, means to connect each pair of upper and lower sliding brackets and means to traverse them in unison. 95

3. Apparatus for shearing metal bars into short lengths constructed with a plurality of shearing cutting heads the blades of which are disposed transversely to the longitudinal axis of the machine, a stationary cross bed provided with slides, a plurality of sliding brackets mounted thereon, means to move the brackets to and fro, a cutting blade detached to each sliding bracket, a reciprocating cross-head provided with 105 slides, means to move the cross-head up and down, a plurality of sliding brackets mounted on the cross-head, a cutting blade detached to each, each upper sliding bracket being connected to a lower sliding bracket 110 to traverse in unison with it. 115

4. Apparatus for shearing metal bars into short lengths constructed with a plurality of shearing cutting heads the blades of which are disposed transversely to the longitudinal axis of the machine, a reciprocating cross head provided with slides, eccentrics by which the cross-head is moved up and down, a plurality of sliding brackets mounted on the cross-head, a cutting blade attached to each bracket, a stationary cross-bed provided with slides, a plurality of sliding brackets mounted thereon, a cutting blade attached to each, a rack affixed to the 120 stationary cross bed, a wheel carried by 125 130
